CLAIM

The ornamental design for a toy motor car, as shown
and described.

DESCRIPTION

FIG. 1 is a front elevational view of a toy motor car
showing my new design;

FIG. 2 is a rear elevational view thereof;

FIG. 3 is a top plan view thereof;

FIG. 4 is a bottom plan view thereof; and

FIG. 5 is a right side elevational view thereof; the side
opposite being a mirror image.

FIG. 2

FIG. 1

FIG. 4

FIG. 3

U.S. Patent
